UNITED STATES PATENT OFFICE.

WILLIAM A. AUSTIN, OF SCRANTON, PENNSYLVANIA, ASSIGNOR OF ONE-HALF TO
THOMAS McHALE, OF SCRANTON, PENNSYLVANIA.

WASHING MACHINE.

Application filed February 2, 1925. Serial No. 6,478.

To all whom it may concern:

Be it known that I, WILLIAM A. AUSTIN, a citizen of the United States, and a resident of Scranton, in the county of Lackawanna and State of Pennsylvania, have invented certain new and useful Improvements in Washing Machines, of which the following is a specification.

The present invention aims to provide a washing machine wherein the clothes may not only be thoroughly washed and cleansed but also rinsed with clear water and blue water and wrung out while in the machine and without the necessity of any handling 15 of the clothes to effect these operations.

Another object of the invention resides in the provision of a machine of this character and having these advantages and which is of simple and durable construction, reliable 20 and efficient in operation and easy and comparatively inexpensive to manufacture and operate.

Other objects and advantages reside in certain novel features of the construction, 25 arrangement and combination of parts which will be hereinafter more fully described and particularly pointed out in the appended claims, reference being had to the accompanying drawings forming part of 30 this specification and in which—

Figure 1 is a view in side elevation showing one embodiment of the invention,

Figure 2 is a fragmentary view in longitudinal section,

Figure 3 is a view in transverse section,

Figure 4 is a view in end elevation, looking at one end of the machine, and

Figure 5 is a similar view looking toward the other end of the machine.

Referring to the drawings, the numeral 1 designates a stationary tank or tub which is mounted on frames or stands 2 and which has doors 3 to provide ready access to the interior of the tank.

A cylindrical drum 4 is arranged in the tank 1 and has end plates 5 and a perforated cylindrical body portion 6 which also has doors 7 to enable access to be had to the interior of the drum. The drum 4 is mounted

for oscillatory movement in any suitable manner but preferably by means of hollow trunnions 8 having flanges 9 suitably fastened to the end plates 5 of the drum, the trunnions being fitted in bearings 10 provided therefor in the ends of the tank 1 and in the stands 2. It is to be understood that suitable packing is provided wherever it is found desirable.

A shaft 11 extends axially through the drum and through the hollow trunnions thereof, the shaft being journaled in the trunnions so as to be free to oscillate independently of the drum and having its ends projecting beyond the drum.

A plurality of sector shaped ribs designated generally at 12 are fixed to the drum 4, each sector shaped rib 12 having a curved bar fastened to the cylindrical body portion of the drum and having radially extending bars 14 connected at their adjacent ends at 70 a point close to but slightly spaced from the shaft 11. A pair of plates 15 is mounted on the ribs 12, the plates 15 being radially disposed and extending lengthwise through the drum from end to end thereof. Each plate 15 is secured to the radial bars of the ribs 12 against which it is fitted. Preferably the plates 15 are perforated. The plates 15 may be connected at their ends so as to completely 80 encase the ribs 12.

A plurality of similar sector shaped ribs designated at 16 are fixed on the shaft 11. The ribs 16 have curved bars 17 disposed adjacent to but slightly spaced from the inner periphery of the drum and having radially extending bars 18 merging into hubs 19 fitted on and fixed to the shaft 11. Plates 20 are fitted against and fastened to the radial bars 18 of the ribs 16 and extend radially from the shaft and lengthwise of the drum. The plates 20 do not engage the ends of the drum but lie closely adjacent thereto. The plates 20 may be connected at their ends so as to completely encase the ribs 16.

Means is provided for moving the drum and the shaft in opposite directions and this means preferably comprises an electric mo-

2
tor 25 having an armature 26 on which a worm 27 is fixed. The worm 27 meshes with a worm wheel 28, the hub of which is loosely fitted on a shaft 29. On one end 5 of the hub of the worm wheel, a clutch member 30 is provided and is designed for engagement with the clutch member 31 splined on the shaft 29 and shifted into and out of engagement with the clutch member 30 by means of a shifting lever 32. Of course the worm wheel 28 and its hub are held against axial movement although free to rotate.

The shaft 29 is journaled in suitable bearings provided therefor on the frames or stands 2 and on the ends of the shaft 29 which project beyond the frames or stands two crank disks 33 are fixed. The crank disks 33 have pins 34 and 35 fixed thereto, the pin 34 of the one crank disk being of opposite throw with respect to the pin 35 of the other disk. Connecting rods 37 and 38 are connected to the crank pins 34 and 35 respectively. The connecting rod 37 is connected by means of a spring connecting element 39 with the shaft 11 while the connecting rod 38 is connected by a similar though oppositely arranged spring connecting element 40 to the drum 4. The spring connecting elements 39 and 40 provide yieldable or elastic connections in the motion transmission means between the driving element or drive shaft 29 and the drum 4 and shaft 11.

35 In operation the clothes are placed in the drum 4 between the plates 15 and the plates 20, there being clothes on both sides of the machine. When the lever 32 is shifted to engage the members of the clutch the drum 4 and the shaft 11 are oscillated in opposite directions so that the clothes are carried through the cleansing fluid which partially fills the tank 1 and the drum 4. The plates 15 being perforated permit the 40 cleansing fluid to course through the clothes. As either set of the coacting plates 15 and 20 approach each other they squeeze the clothes between them and express the cleansing fluid from the clothes, thereby more effectively washing and cleaning the same.

45 After the clothes have been thoroughly washed, the cleansing fluid is withdrawn through a valve controlled outlet 50 provided in the lower portion of the tank 1. The cleansing fluid is replaced by clear rinsing water or fluid and the rinsing water or fluid is in turn replaced by blueing water or the like if blueing is desirable. After 55 these several operations have been completed the valve controlled outlet is opened and thereafter the drum and the shaft are oscillated for a time so that the plates 15 and 20 will work to the end of wringing the clothes dry. In this way the same instrumentalities of the machine perform all

of the operations necessary to the washing of the clothes and it is not necessary to handle the clothes to perform any of these operations. When the clothes are taken from the machine they are ready to be 70 hung upon a line or otherwise dried.

The elastic connecting elements or springs 39 and 40 permit the operating means or driving mechanism for the drum and shaft to work equally well with various batches 75 of clothes.

I claim:

1. In a washing machine, a tank, an oscillating drum within the tank, an independently oscillatable shaft extending 80 through the drum, a plate connected to the shaft and movable therewith, and a plate connected with the drum and movable therewith, at least one of said plates being formed with openings, and means for moving the drum and the shaft in opposite directions.

2. In a washing machine, a tank, an oscillating drum within the tank, an independently oscillatable shaft extending 90 through the drum, a plate connected to the shaft and movable therewith, and a plate connected with the drum and movable therewith, at least one of said plates being formed with openings, and means for moving the drum and the shaft in opposite directions, said means including a driving element and motion transmission means between the driving element and the shaft and between the driving element and the drum, said motion transmission means including elastic elements.

3. In a washing machine, a tank, an oscillating drum within the tank, an independently oscillatable shaft extending 105 through the drum, a plate connected to the shaft and movable therewith, a plate connected to the drum and movable therewith, at least one of said plates being formed with openings, and means for moving the drum and the shaft in opposite directions and including a rotatable drive shaft, crank disks fixed to said drive shafts and having crank pins, the pin of one crank being opposite to the pin of the other, connecting rods pivoted to the crank pins and elastic connecting elements between the rods and the shaft and drum.

4. In a washing machine, a tank, an oscillating drum within the tank, an independently oscillatable shaft extending 120 through the drum, a plate connected to the shaft and movable therewith, a plate connected to the drum and movable therewith, at least one of said plates being formed with openings, and means for moving the drum and the shaft in opposite directions and including a rotatable drive shaft, crank disks fixed to said drive shaft and having 125 crank pins, the pin of one crank being oppo-

site to the pin of the other, connecting rods pivoted to the crank pins, and spiral springs between the rods and the shaft and drum.

5. In a washing machine, a tank, an oscillating drum within the tank, said drum being cylindrical and having perforations in its periphery, an independently oscillatable shaft extending axially through the drum,

sector shaped ribs fixed to the shaft, sector shaped ribs fixed to the drum, plates extending lengthwise of the drum and fixed to the radial bars of said sector shaped ribs, certain of said plates being perforated, and means for moving the drum and shaft in opposite directions.

WILLIAM A. AUSTIN.
